SASH CORNER CONSTRUCTION

Charles A. Pressnall, Elkhart, Ind., assignor to
The Adlake Company, Chicago, Ill., a corpora-
tion of Illinois

Application June 10, 1947, Serial No. 753,644

6 Claims. (Cl. 189—76)

1

This invention is concerned with improvements in window sash construction.

It is an object of the invention to provide a window sash construction of the type which is particularly adapted to be made of metal, such as extruded aluminum sections, having improved means for securing the end of the balance tape to the vertical side frame member of the sash.

It is a more specific object of the invention to provide a metal window sash construction having a stainless steel plate adapted to be secured to the upper corner of the sash and provided with a hook or tongue portion extending downwardly along the side frame member of the sash constituting an anchoring means for detachably receiving the end connecting member of a balance tape.

These and other objects of the invention will be apparent from a description of the preferred form thereof which is shown by way of illustration in the accompanying drawings, wherein:

Fig. 1 is a perspective view of an upper corner of a sash having incorporated therein a construction embodying the principles of the invention;

Fig. 2 is an exploded view showing in perspective the corner of the sash, the depending end of a balance tape and the anchor plate for securing the end of the tape to the sash;

Fig. 3 is a side elevation of the corner of the sash with portions of the weather strip member broken away; and

Fig. 4 is a section on the line 4—4 of Fig. 3.

The sash illustrated in Fig. 1 is a portion of a lower sash which is adapted to be mounted in the frame of either a single hung or double hung sash type window. While a lower sash is illustrated, the principles of the invention may be applied to an upper sash in the same manner.

The top horizontal rail member 10 of the sash is secured at its end in abutting relation to the vertical side member 11 to form the corner joint. The members 10 and 11 may be secured to each other by bolts or similar fastening means.

The vertical side member 11 comprises a front plate or flange member 12, a rearwardly extending web member 13 and a rear flange member 14, preferably formed integrally as an extruded metal section.

The front member 12 is provided at its inner edge with an inwardly directed flange 15 (Fig. 4) which forms one side of the glazing channel for the glass pane (not shown). The inner edge of the rear flange member 14 extends only to the web member 13 and is there provided with a thickened portion 16 having a relatively narrow

inwardly opening, vertically extending groove 17 for receiving the glazing bead (not shown) which secures the pane in the glazing channel.

The front flange member 12 is provided adjacent its outer edge with a forwardly facing, vertically extending channel-like recess or groove 18 and the rear flange member 14 is provided adjacent its outer edge with a similar groove 19 which faces rearwardly.

A weather strip channel member 20 having parallel legs 21 and 22 is provided, on its outer surface, with a non-metallic weather strip 23, the edges of which are secured to the channel member 20 by bead-like formations 24 and 25 provided by curling outwardly the edges of the legs 21 and 22. The weather strip member is mounted on the vertical sash member 11 by positioning the bead formations 24 and 25 in the parallel grooves 18 and 19 of the sash member.

Transversely aligned slots 26 and 27 are provided a short distance from the top of the sash by cut-out portions in the outer edges of the members 12 and 14 for a purpose which will be described.

A tape end anchor member 28 is provided which is preferably made of stainless steel plate. It is cut and shaped to provide a relatively wide top or horizontal portion 29 and a relatively narrow integral leg portion 30 which extends downwardly of the top plate 29 and terminates in an outwardly offset tongue or hook portion 31. The top plate 29 is of a size sufficient to cover the top of the vertical sash member 11 and to extend a short distance over the top surface 32 of the rail member 10. The leg portion 30 is of a width which adapts it to be positioned in the channel or groove formed between the inner surfaces of the flange members 12 and 14 and is provided adjacent its lower end with lateral extensions 33 and 34 which fit into the transversely aligned slots 26 and 27 in the edges of the flange members 12 and 14. The offset portion 35 connecting the leg 30 and the hook 31 forms a shoulder which is engaged by the apertured attaching member 36 on the end of the balance tape 37 when the members are in assembled relation as in Fig. 1.

The anchor member 28 is retained in position by the engagement of the lateral extensions 33 and 34 in the transverse slots 26 and 27 and the tension in the balance tape 37. As an additional means for securing the anchor member 28 to the sash it is preferred to provide an aperture 38 in the top plate member 29 and a threaded aperture 39 in the rail member 10 for reception of a secur-

ing screw 40 which securely fastens the anchor member 28 in position.

As clearly shown in Figs. 1 and 3 the outer corners 41 and 42 of the top plate member 29 extend over the grooves 18 and 19 in the members 12 and 14 of the vertical sash frame member 11 and provide abutment stops for the upper ends of the bead formations 24 and 25 on the weather strip channel 20. The lower end of the weather strip channel 20 may be secured in any desired manner against downward movement.

The anchor plate 28 is disengaged from the sash by removing the securing screw 40 and moving plate 28 outwardly to free the lateral extensions 33 and 34 from the slots 26 and 27, whereupon the end of the balance tape 31 is released. The weather strip carrying channel may also be removed vertically of the sash since the bead formations 24 and 25 are slidably positioned in the grooves 18 and 19.

While specific materials and details of construction have been referred to, it will be understood that other materials and details of construction may be resorted to within the spirit of the invention.

I claim:

1. In a sash corner construction having a horizontal top rail and a vertical side frame member secured in abutting relation adjacent their ends with said side frame member having transversely spaced outwardly directed front and rear side flanges and transversely aligned outwardly opening slots in said side flanges adjacent the top thereof, a tape end anchor member having a horizontally directed plate portion extending over the end of said side frame member and an end portion of said top rail, and a vertically directed plate portion extending downwardly along the outer edges of said side flanges, said horizontal plate portion having an aperture therein for receiving a fastening element to secure the same to said top rail, said downwardly directed vertical plate portion having a hook formation for receiving in detachable relation the end of a balance tape and laterally extending members thereon adapted to be positioned in said transverse slots whereby to secure said plate to said sash corner in tape anchoring position.

2. In a sash corner construction having a vertical side member and a cross rail in end abutting relation with the side of said side member, said side member being provided with parallel transversely spaced front and rear flanges having oppositely facing vertical grooves in the front and rear faces adjacent the outer edges thereof and transversely aligned outwardly opening slots in the outer edges of said flanges which slots are located a short distance from the end of said side member, said oppositely facing grooves being adapted to receive a weather strip channel of generally U-shaped section having edge formations slidably positioned in said vertical grooves and encompassing the outer edges of said member, a balance tape end retaining means comprising an angular plate member having a vertically directed leg positioned along the outer edges of said flanges between said side member and said weather strip channel, said vertically directed leg having laterally extending abutment portions receivable in said transverse slots and an outwardly extending hook for receiving the end of said balance tape, said tape end retaining means having a horizontal leg providing abutment formations at the end of said side member

extending laterally over the ends of said vertical grooves for engagement by the end of said weather strip channel to position the same on the side member in encompassing relation with said vertical leg of said tape end retaining means.

3. A balance tape anchor plate adapted for attachment to the top corner of a window sash which sash is characterized by a vertical side frame member provided with outwardly directed transversely spaced vertical side flanges and transversely aligned outwardly opening slots in the side flanges adjacent the top thereof, said anchor plate comprising a body portion adapted to be positioned in the space between the side flanges of the frame member, laterally extending members on the body portion adapted to be positioned in the transverse slots in the side flanges of the frame member and a downwardly directed hook formation for receiving in detachable relation the end of a balance tape.

4. A balance tape anchor member adapted for attachment to the corner of a window sash which sash includes a vertical side frame member provided with outwardly directed transversely spaced vertical side flanges and transversely aligned outwardly open slots in the side flanges adjacent the end thereof, said anchor member comprising an angle plate having a horizontal leg adapted to be positioned over the end of the side frame member and a vertical leg adapted to be positioned along the vertical side flanges of the side frame member, said vertical leg having laterally directed extensions which are adapted to be seated in the slots in the side flanges of the side frame member and a downwardly extending portion forming a hook for receiving the end of a balance tape.

5. A balance tape anchor member adapted for attachment to the corner of a window sash which sash includes a vertical side frame member provided with outwardly directed transversely spaced vertical side flanges for receiving in sliding relation thereon a channel-shaped weather strip and transversely aligned outwardly opening slots in the outer edges of the side flanges spaced inwardly of the end thereof, said anchor member comprising an angle plate having a horizontal leg adapted to be positioned over the end of the side frame member and a vertical leg adapted to be positioned along the vertical side flanges of the side frame member, said horizontal leg being of sufficient size to extend beyond the lateral faces of the vertical side flanges and form an abutment for the end of a weather strip, said vertical leg having laterally directed extensions which are adapted to be received in the slots in the vertical side flanges and said vertical leg terminating in a downwardly extending portion forming a hook for receiving the end of a balance tape.

6. A balance tape anchor member adapted for attachment to a window sash corner construction which is characterized by a vertical side frame member provided with outwardly directed transversely spaced vertical side flanges and transversely aligned outwardly opening slots in the side flanges adjacent the end thereof and which is further characterized by a cross rail member in end abutting relation with the inner side of the side frame member adjacent the end thereof, said anchor member comprising an angle plate having a horizontal leg adapted to be positioned over the end of the side frame member and a vertical leg adapted to be positioned along the vertical side flanges of the side frame member,

said horizontal leg being of sufficient size to extend beyond the side faces of the side frame member and over a portion of the end of the cross rail member, said vertical leg having laterally directed integral portions which are adapted to be positioned in the slots in the side flanges of the side frame member and said vertical leg having an end portion in outwardly and downwardly extending hook forming relation for receiving the end of a balance tape.
